ABSTRACT OF THE DISCLOSURE

A ribbon burner and electrode assembly wherein an elongate tubular burner having longitudinally extending burner ports is ignited by an electrode supported by an insulating housing extending coextensively with the burner, the electrode being mounted for rotational movement from a predeterminable position in which the charge transmitting end of the electrode is spaced from the burner ports to a position in which it is adjacent the burner ports and scrapes graphite and like deposits off the ports, and wherein spring mechanism biases the electrode to return to original position so that when released the electrode will ignite the fuel gas issuing from the ports as it returns to original position and creates a gap across which an igniting spark will jump.

It is conventional practice to use a graphite lubrication of the type wherein graphite is dispersed in kerosene to maintain chains traveling within bakery ovens and the like adequately lubricated. Difficulty has been encountered in electrically lighting fuel gas burners in such ovens because graphite tends to collect or deposit on the burner ports. Another problem which has been encountered in such ovens is that of maintaining the proper gap between the electrode edge and the burner ports to provide optimum performance. Even though the gap is properly set in the first place, ignition difficulties have been encountered, following the replacement of electrodes which have been removed for cleaning and replaced by bakery personnel.

One of the prime objects of the present invention is to provide a burner assembly having a disassemblable electrode member which is so designed that proper positioning of the electrode edge relative to the burner ports is rendered automatic upon initial installation or replacement following cleaning, and the danger of the flag being mispositioned so that raw gas does not ignite and is emitted to create a dangerous explosive condition in the oven is eliminated.

A further object of the invention is to design a burner and electrode assembly which does not require use of a peep-hole to adjust the position of the electrode, and which cannot slip out of preadjusted position.

Another object of the invention is to design a burner and electrode assembly which is operable to remove graphite and other "shorting" deposits from the burner ports.

Still another object of the invention is to provide a ribbon burner electrode assembly which is positive in operation and wherein the manipulative parts which are used to effectuate ignition are located outside the oven and can be conveniently operated.

Still another object of the invention is to provide a very efficient and highly reliable ribbon burner and electrode assembly of relatively simple construction which can be very economically manufactured and assembled for sale to the baking industry for use in the baking ovens of commercial bakeries.

Other objects of the invention will become apparent from the accompanying description and appended claims.

2

In the drawings:

FIGURE 1 is a fragmentary, sectional, top plan view, taken through an oven side wall and illustrating the novel oven burner and electrode assembly which is provided for electrically igniting fuel gas which issues from the side ports of the burner.

FIGURE 2 is a fragmentary, front elevational view thereof.

FIGURE 3 is an enlarged, fragmentary view of certain electrode operating parts, taken on the line 3—3 of FIGURE 2.

FIGURE 4 is a fragmentary, front elevational view thereof.

FIGURE 5 is an enlarged fragmentary view showing the electrode flag swung over to engage the burner port grill members.

In my United States Patent No. 3,352,346, entitled "Ribbon Burner Electrode Assembly," issued Nov. 14, 1967, I disclose a burner and electrode assembly which does an excellent job of locating the charge transmitting end of an electrode flag relative to the burner ports. This assembly, however, does not have the capability of removing deposits from the burner ports, and in some installations this latter capability is of extreme importance.

Referring now more particularly to the accompanying drawings in which only a preferred embodiment of the invention is illustrated, a letter W generally indicates the insulated side wall of an enclosed baking oven of conventional design which includes top and bottom walls as well as side walls, and is of the type used in the baking of bread and other bakery products. A fuel gas burner assembly generally designated B is supported in position on the side wall of the oven and includes a tubular casing member 10 projecting longitudinally into the oven usually transversely of the length thereof. A typical installation showing a tunnel oven of considerable length, in which a large number of such burner and electrode assemblies are used in transverse disposition, is disclosed in United States Patent No. 2,801,686.

The burner B which is shown may be considered to be of exactly the construction disclosed in my United States Patent No. 3,172,460, and accordingly the burner B will not be described in detail. As disclosed in that patent, the burner casing or barrel 10 is closed at its inner end by an end wall 11 (FIGURE 5) and a longitudinally extending slot 12 is provided in one of its sides for accommodating the port forming ribbon or grill assembly generally designated R which is made up of electrically conductive metal strips of the character disclosed in both of my aforementioned patents forming burner ports p. At its outer end, adjacent the side wall W, the burner casing 10 is coupled by sleeve 13 to a housing section 14 which is fixed within a burner box 15 extending through an opening 16 in the wall W. A cover plate 17 for the box 15 may be secured to the wall W by cap screws 18. A premixed hydrocarbon gas and air mixture under a predetermined pressure is supplied to the burner 10 which preferably includes a manifold assembly 19 of the character disclosed in my United States Patent No. 3,172,460, 60 via a supply pipe 20 extending from any suitable conventional fuel gas source.

Extending coextensively with the burner assembly B is a removable contiguous igniter unit, generally identified by the letter I, which includes a casing or housing 21 extending through an opening 22 provided in the wall 17 of burner box 15. As in my aforementioned Patent No. 3,353,346, an axially projecting electrode rod 23 is fixed within the casing 21, and suitably insulated therefrom. An offset flag 24 is fixed to the rod 23 and has a charge transmitting edge 24a, and both the rod 23 and flag 24 are formed of electrically conductive material. It is to be

understood that rod 23 extends back through the casing 21 in the manner indicated in United States Patent No. 3,352,346 to connect with a charge supplying wire carrying sheath 25 in the usual manner.

At its front end the casing 21 is supported for rotation by a yoke Y, open at its outer end to permit removal of the casing 21, which is secured to the burner casing 10. At its rear end a crank arm handle or lever generally designated 26 is secured to the casing 21. The crank arm or actuator lever 26 is provided with a clamp ring 26a and may be securely clamped to the reduced rear end 21a of the electrode casing 21 by suitable means such as a capscrew 26b. A spring assembly generally designated 27 is provided for maintaining the arm 26 and accordingly the flag 24, in the position shown in FIGURE 2 wherein the flag is spaced from the burner ports p. As FIGURES 3 and 4 indicate, the spring assembly 27 includes an angle member 28, adjustably secured to the burner box front plate 17 by means such as a bolt 29 extending through an elongated slot 30. A bolt member 31, extending freely through an opening 26c in the arm 26, has a threaded end received in a threaded opening 32 provided in the angle support member 28 to function as a spring guide for a coil spring 33 which is interposed between the support 28 and a washer 34 on bolt member 31.

Provided in the same manner, as in my aforementioned Patent No. 3,172,460, above the igniter electrode I, is the peep-hole cover 35, which is mounted on an arm 37 to swing outwardly and upwardly about a pin 36. The cover 35 covers an opening in plate 17 which, when the cover 35 is swung upwardly, permits the workman to see into the interior of the oven. As previously indicated, it will be necessary from time to time to remove the electrode assembly I in the manner indicated in my Patent No. 3,352,346 for cleaning and to replace it, and the peep-hole will permit the workman to do this without physically entering the oven.

To remove the electrode assembly the cap screw 29 is first removed. It is then merely necessary to grasp the end 26a of the casing 21 and swing the casing 21 outwardly laterally from the burner B and out of the yoke 26. When the casing 21 is then moved rearwardly, the assembly I can be tilted to pass the flag 24 out the opening 22. Reinsertion of the electrode assembly I is also a simple matter and can be accomplished by inserting the flag 24 in tilted position through opening 22 and then replacing the casing 21 in the yoke 26. After this, the cap screw 31 can be replaced. It is desirable to maintain a gap of about .020 of an inch between the flag edge 24a and the ribbon burner assembly. Because of the unique construction of the present burner and electrode assembly, it is not necessary to maintain the gap by estimating whether or not it is proper when looking through the peep-hole into the interior of the oven. Instead, the handle 26 can be pressed upwardly in the clockwise direction of the arrow a in FIGURE 2 until the flag 24 engages the ribbon burner elements R, and the bolt 31 can then be tightened down to maintain it in this position. The bolt 31 can then be backed off the required predetermined number of revolutions which will automatically provide the proper gap between the edge 24a and the ribbon burner elements R for optimum sparking.

In the operation of the device the burner is lighted by the operator grasping the protruding end of the angle 28 and the arm 26 between the thumb and forefinger of one hand, for instance, and pressing the handle 26 toward the protruding end of the angle support 28 to compress spring 33. The flag 24 will be moved in a clockwise direction to the position in which it is shown in FIGURE 5, and in so doing will scrape graphite deposits from the ribbon burner element R. With the electrical power "on," when arm 26 is released and is sharply returned by the spring 33 to original position, a spark jumps the gap and ignition is achieved virtually every time at the instant gas

begins to issue from the burner ribbon assembly R, thus avoiding the creation of the dangerous explosive atmosphere which might otherwise result. If, for some reason, the graphite deposit should not be completely removed, to the extent that the electrical "short" is removed, the lever 26 can, of course, be jiggled to fully dislodge the graphite and "break the short" so that ignition can occur.

It is to be understood that various changes may be made in the construction shown and described to effectuate the same or similar results without departing from the spirit of the invention or the scope of the appended claims. The foregoing descriptive matter and drawings are intended only as illustrative, and the invention is defined by the claims.

15 I claim:

1. A burner assembly comprising: an elongate tubular burner having longitudinally extending burner port means; means for supplying fuel gas to said tubular burner and burner port means; electrode rod support and insulating means extending generally coextensively with said burner and having an electrode with a charge transmitting end; means mounting said electrode rod for movement from a position in which said electrode charge transmitting end is spaced from said burner port means through a path of movement in which it wipes said burner port means; and means for supplying an electric charge to said electrode to ignite fuel gas issuing from said port means.

2. The combination defined in claim 1 wherein spring means biases said electrode rod to the position wherein the electrode end is spaced from the burner port means.

3. The combination defined in claim 1 in which said electrode rod support and insulating means extends through an oven wall and has a rear end extending outside said wall; a crank handle fixed on said rear end; and adjustable spring means biasing said handle to an adjustable rotary position in which said electrode end is spaced from said burner port means.

4. A burner assembly comprising: an elongate tubular burner having longitudinally extending burner port means; means for supplying fuel gas to said tubular burner and burner port means; electrode rod support and insulating means extending generally coextensively with said burner and having an electrode with a charge transmitting end; means mounting said electrode rod for rotational movement from a position in which said electrode charge transmitting end is removed from said burner port means to a position in which it is adjacent said burner port means and means for supplying an electric charge to said electrode rod to ignite fuel gas issuing from said port means; said electrode end wiping across said burner port means and scraping carbon deposits therefrom in moving to said adjacent position.

5. A burner and oven wall assembly comprising: an elongate tubular burner having longitudinally extending burner port means; means for supplying fuel gas to said tubular burner and burner port means; electrode rod support and insulating means extending generally coextensively with said burner and having an electrode with a charge transmitting end; means mounting said electrode for rotational movement from a position in which said electrode charge transmitting end is removed from said burner port means to a position in which it is adjacent said burner port means; means for supplying an electric charge to said electrode rod to ignite fuel gas issuing from said port means; said electrode rod support and insulating means extending through said oven wall and having a rear end extending outside said wall; a crank handle fixed on said rear end; and spring means biasing said handle to the rotary position in which said electrode end is removed from said burner port means.

6. A burner assembly comprising: an elongate tubular burner having longitudinally extending burner port means; means for supplying fuel gas to said tubular burner and burner port means; electrode rod support and insulating means extending generally coextensively with said burner

and having an electrode with a charge transmitting end; means mounting said electrode rod for rotational movement from a position in which said electrode charge transmitting end is removed from said burner port means to a position in which it is adjacent said burner port means; means for supplying an electric charge to said electrode rod to ignite fuel gas issuing from said port means; and actuator means for rotating said electrode rod including an actuating arm secured to said electrode rod, a bracket spaced from said arm, and a biasing element mounted between said arm and said bracket.

7. The combination defined in claim 5 in which a support is mounted in fixed position at a spaced distance from

the crank handle in the direction of rotation of said handle to move the electrode end toward the burner port means.
